United States Patent Office

Des. 208,260
Patented Aug. 8, 1967

208,260

FOOD SERVICE TRAY

Charles Meyer, Jr., Lynchburg, Va., assignor to Chefcraft
Associates, Lynchburg, Va., a partnership

Filed Oct. 14, 1966, Ser. No. 4,286

Term of patent 14 years

(Cl. D44—10)

FIGURE 1 is a perspective view of a food service tray embodying my new design;

I claim:

The ornamental design for a food service tray, as shown.
